UNITED STATES PATENT OFFICE

122,011

DESIGN FOR A DISPLAY RACK

Ernest R. Erickson, Des Moines, Iowa, assignor to
C. E. Erickson Company, Incorporated, Des
Moines, Iowa, a corporation of Iowa

Application May 6, 1940, Serial No. 92,175

Term of patent 7 years

To all whom it may concern:

Be it known that I, Ernest R. Erickson, a citizen of the United States and a resident of Des Moines, in the county of Polk and State of Iowa, have invented a new, original, and ornamental Design for a Display Rack, of which the following is a specification, reference being had to the accompanying drawing, forming part thereof.

Figure 1 is a perspective view of a display rack showing my design; and

Figure 2 is an enlarged fragmentary perspective view thereof, two of the shelves being omitted

and the bottoms of the corner supporting elements being shown broken away;

Figure 3 is another perspective view of the display rack, on the same scale as Figure 1; and

Figure 4 is an enlarged vertical sectional view thereof taken on the line 4-4 of Figure 1, the corner supporting elements being shown broken away.

I claim:

The ornamental design for a display rack, substantially as shown and described.

ERNEST R. ERICKSON.
